(57) **CLAIM**

The ornamental design for a magnetic key holder, as shown and described.

DESCRIPTION

FIG. 1 is a perspective view of a magnetic key holder showing the new design;

FIG. 2 is another perspective view thereof;

FIG. 3 is a front elevation view thereof;

FIG. 4 is a back elevation view thereof;

FIG. 5 is a left-side view thereof;

FIG. 6 is a right-side view thereof;

FIG. 7 is a top plan view thereof;

FIG. 8 is a bottom plan view thereof;

FIG. 9 is a perspective view in an open position thereof;

FIG. 10 is an enlarged view of the encircled portion in FIG. 1;

FIG. 11 is an enlarged view of the encircled portion in FIG. 1; and,

FIG. 12 is an enlarged view of the encircled portion in FIG. 9.

The broken lines depict portions of the magnetic key holder that form no part of the claimed design.

The dash-dot-dash lines represent boundary lines that form no part of the claimed design.

1 Claim, 12 Drawing Sheets

EX PARTE
REEXAMINATION CERTIFICATE

THE PATENT IS HEREBY AMENDED AS 5
INDICATED BELOW.

AS A RESULT OF REEXAMINATION, IT HAS BEEN
DETERMINED THAT:

The claim 1 is cancelled. 10
